UNITED STATES PATENT OFFICE.

PAUL PIERSON, OF CHICAGO, ILLINOIS.

PASTING-MACHINE.

1,128,501.

Specification of Letters Patent. Patented Feb. 16, 1915.

Application filed August 30, 1911. Serial No. 646,826.

To all whom it may concern:

Be it known that I, PAUL PIERSON, a resident of Chicago, in the county of Cook and State of Illinois, have invented certain new and useful Improvements in Pasting-Machines, of which the following is a full, clear, and exact description.

The invention relates to machines for applying an agglutinant to strips of cloth or paper, which are particularly adapted for use on cigar or other boxes, the latter usually having strips pasted along the corners to conceal the joints and to improve the appearance of the finished box.

15 The invention designs to provide an improved machine which facilitates the work of the operator in applying strips to boxes, by applying the agglutinant to one face of the strip and feeding it forward intermittently at the will of the operator, as necessary in the progress of the work on the boxes, the strip being taken from a roll, fed through mechanism for applying the agglutinant and into position to be severed 25 by the operator in pieces of the desired length.

The invention consists in the several novel features hereinafter set forth and more particularly defined by claims at the conclusion hereof.

In the drawings, Figure 1 is an end elevation of a machine embodying the invention, the foot-lever being shown depressed or in position assumed after a length of the strip has been fed forwardly and before the lever is retracted. Fig. 2 is a section on line 2—2 of Fig. 1. Fig. 3 is a central vertical section of the agglutinant applying and paper-feeding mechanism. Fig. 4 is a vertical section taken on line 4—4 of Fig. 3.

40 The machine, for the convenience of the operator, is mounted upon a table 10 and a continuous web of paper 11 to which the agglutinant is to be applied, is wound upon a roll 12, which is held on a shaft 13, which rests in open bearings 14 on brackets 15, which are secured upon the top of table 10. A presser-lever 16 is adapted to engage the outside of the roll of paper 11 to keep the strip taut or to prevent unwinding of the roll except by the paper-feeding mechanism. This presser-lever is pivoted as at 17 in brackets 15 and a spring 18 is applied to said lever to frictionally engage the roll of paper.

45 50 55 The device for drawing the strip of paper from roll 11 and feeding it forwardly

comprises an upper roll 19 and a lower co-acting roll 20 between which the strip of paper passes. A roll 21 for guiding the paper is disposed between the feed-rolls and 60 the roll of paper 11 and this roll 21 is mounted in open bearings 26 of a frame 23. The strip of paper is fed forward of rolls 19, 20 by endless wires 24 which underlie the strip and pass through peripheral 65 grooves 25 in roll 20 around a correspondingly grooved roll 26' at the rear end of the machine and another correspondingly grooved roll 27 at the front of the machine. Roll 26' is mounted in bearings 28 formed 70 in frame 23, and roll 27 is mounted in blocks 29 which are slidably mounted in guides 30 formed in brackets 31 respectively, which are secured to the table 10 at the front end thereof. A spring 32 is applied to each 75 bearing 29 to exert sufficient pressure upon said bearings, to cause roll 27 to keep the endless wires 24 taut and prevent them from sagging between the rolls around which they pass. The force of springs 32 may be varied 80 by screws 33. The wires 24 carry the strip forwardly of and away from the feed-rolls, and into convenient position to be manipulated by the operator. Roll 21 causes the web to be passed onto wires 24 before it 85 passes between rolls 19, 20, to insure uniform contact between the paper and the agglutinant-applying roll 20, despite variation of the size of the roll of paper. Roll 20 is secured to a shaft 35 which is mounted in 90 bearings 36 of frame 23 and the upper feed-roll 19 is secured to a shaft 37 which is journaled in blocks 38. Said blocks are mounted to slide in guides 39 on frame 23, and springs 40 are applied to said bearing blocks 95 to press roll 19 toward the co-acting roll 20. Screws 41 extend through top plates 42 to adjust the force of said springs, so that the pressure against the paper may be varied to cause paste in proper amount to be applied 100 to the paper by roll 20.

Roll 20, in addition to co-acting with roll 19 to feed the strip forwardly, serves to apply the agglutinant to the under side of the strip. A receptacle 42' is formed in 105 frame 23 and contains the liquid-agglutinant. A roll 43 rotates in the agglutinant and is secured to a shaft 44 which is mounted in bearings 45 of frame 23. This roll 43 transfers the agglutinant in regular quantity to the roll 20 with which the upper portion of roll 43 contacts. A wiper 46, con-

sisting of a strip of felt or rubber, is suitably secured in the receptacle to remove the excess agglutinant from roll 43. A similar wiper 47 is mounted to engage the periphery of roll 20 to prevent an over-supply of agglutinant to the under side of the paper. By this means, the agglutinant will be applied to the underside of the web of paper from roll 11 as it passes between rolls 19 and 20, and wires 24 upon which the strip with the agglutinant thereon rests, will support and carry the strip forwardly, into position to be removed by the operator.

Mechanism is provided for intermittently operating the paper-feed and agglutinant-applying mechanism, so that during each operation a portion of the web, corresponding approximately to the length of strip desired for the application to a box, will be fed forwardly into position to be removed by the operator and applied to the box. It will be understood that in this work, the length of the strips desired frequently or constantly vary, because the boxes to which the strips are to be applied vary considerably and the work of applying the strips can be facilitated if each strip of paper severed from the continuous length is approximately of the length of one end or side of the box. This mechanism is operable by a foot-lever or treadle 48 which is pivoted in a bracket 49, which is secured to the floor and operated in one direction or retracted by a spring 50. A rod 51 has its lower end connected to lever 48 and its upper end to a sprocket chain 52 which extends around a sprocket-wheel 53 and is connected to a rod 53' to which a spring 54 is applied to retract the chain after each operation of lever 48. Sprocket-wheel 53 has a one-way operating connection with a shaft 57 which is journaled in a bracket 58 on table 10, comprising one-way clutch teeth on the hub of sprocket-wheel 53 and co-acting teeth on a disk or member 59 which is rigidly secured to said shaft, the sprocket-wheel being loose on the shaft. A spring 60 coiled around shaft 57 holds the sprocket wheel normally in engagement with said member. By this means, downward movement of lever 48 will operate shaft 57 in one direction, to operate the paper-feed and agglutinant-applying devices, and during the retraction of lever 48, shaft 57 and the paper-feed and agglutinant-applying devices will remain stationary. Shaft 57 serves to drive roll 19, by means of a gear-wheel 61 secured to said shaft and meshing with a pinion 62 secured to the shaft of said roll. Roll 20 is operated by gears 63 and 64 secured to the shafts of rolls 19 and 20, respectively. Roller 43 is driven by a gear 65 which meshes with gear 64. Endless wires 24 are driven in synchronism with the paper-feed, by a pulley 66 secured to rotate with gear 64, a belt 67, and a

pulley 68 on the shaft of roller 26'. Roller 27 is driven by the wires 24.

The strip of paper on wires 24 having the agglutinant applied to its under side passes beneath a cross-bar or cutter 69 which is held in brackets 70 which are secured to table 10. This cutter serves as means which permits the operator to tear off that portion of the strip in front of the cutter-bar, from the web.

The lower portion of wires 24 pass over a cleaner or wiper 72 which is secured on table 10 to prevent the agglutinant from accumulating on said wires. A table or support 75 is provided adjacent roll 27, to serve as a support for the boxes to which the strips are to be applied, so that they will be in convenient position to have the strips applied thereto.

The operation of the improved machine will be as follows: During each operation of lever 48, the rolls 19 and 20 will draw the paper from roll 11 and roll 20 will apply agglutinant to the under face of the strip as it passes between these rolls. The paper with the agglutinant thereon, will be carried forwardly under cutter 69, by endless wires 24, into position to be grasped by the operator and torn off at cutter 69. The operator may then apply this strip to the box. By discontinuing the downward movement of lever 48 at different points, the paper-feed will be varied, so that the length of the strip in front of cutter 69 will vary and the operator may readily tear off the pasted strips in the different lengths desired. During the return or upward stroke of lever 48 the paper-feed will remain idle and in this manner the mechanism may be intermittently operated at will to apply agglutinant to successive portions of desired and varied length of the web and the paper will be held upon the wires 24 in convenient position to be removed and severed from the remaining portion of the strip and then applied to a box. The invention thus provides an improved machine for feeding the strip of paper and applying an agglutinant thereto in lengths desired and which materially facilitates the work of the operator in applying agglutinant to the strips and the latter to the boxes.

The invention is not to be understood as restricted to the details set forth, since these may be modified by the skilled mechanic within the scope of the appended claims, without departing from the spirit and scope of the invention.

Having thus described the invention what I claim as new and desire to secure by Letters Patent is:

1. In a machine of the character described, the combination of a pair of feed rolls for a continuous strip of material, means for supplying agglutinant to one of the rolls, a stationary cutter, an endless conveyer for sup-

porting the strip after the agglutinant has been applied thereto and extending from one of the rolls to a point beyond the cutter to support the portion of the strip which is to be severed, and mechanism for conjointly operating said rolls and said conveyer, the latter being disposed to support a portion of the strip where it will be torn off by the stationary cutter as said strip portion is removed from the conveyer.

2. In a machine of the character described, the combination of a pair of feed rolls for a continuous strip of material, means for supplying agglutinant to one of the rolls, a stationary cutter, an endless conveyer for supporting the strip after the agglutinant has been applied thereto and extending from one of the rolls to a point beyond the cutter to support the portion of the strip which is to be severed, and mechanism for intermittently and conjointly operating said rolls and said conveyer, said mechanism being operable to advance strips of different lengths beyond the cutter, the conveyer supporting the strip at a point where the portion to be severed will be torn off by the stationary cutter as said portion is removed from the conveyer.

3. In a machine of the character described, the combination of a pair of feed rolls for a continuous strip of material, means for supplying agglutinant to one of the rolls, a stationary cutter, an endless conveyer for supporting the strip after the agglutinant has been applied thereto and ex-

tending from one of the rolls to a point beyond the cutter to support the portion of the strip which is to be severed, and mechanism for intermittently and conjointly operating the rolls and the conveyer comprising a vertically movable lever, a one-way driving connection and a flexible connection between the lever and the one-way connection, the lever being operable to operate the connection any desired extent according to the length of the strip to be severed, the conveyer being disposed to support a portion of the strip where it will be torn off by the stationary knife as the strip is removed from the conveyer.

4. In a machine of the character described, the combination of a pair of feed rolls for a continuous strip of material, one of which has peripheral grooves therein, means for supplying agglutinant to one of the rolls, a stationary cutter, endless wires for supporting and conveying the strip after the agglutinant has been applied and extending under, adjacent and beyond the cutter, and mechanism for conjointly operating said rolls and said wires to feed a portion of the strip beyond the wires, said wires being extended to support said portion of the strip and disposed so that said portion will be torn off by the knife as it is removed from the wire.
